T. C. MORRIS.
FEEDING ROLLER.
APPLICATION FILED APR. 22, 1921.

1,409,395.

Patented Mar. 14, 1922.

UNITED STATES PATENT OFFICE.

THOMAS C. MORRIS, OF VREDENBURGH, ALABAMA, ASSIGNOR TO E. C. ATKINS AND COMPANY, OF INDIANAPOLIS, INDIANA, A CORPORATION.

FEEDING ROLLER.

1,409,395.

Specification of Letters Patent. Patented Mar. 14, 1922.

Application filed April 22, 1921. Serial No. 463,691.

To all whom it may concern:

Be it known that I, THOMAS C. MORRIS, a citizen of the United States, residing at Vredenburgh, Monroe County, Alabama, 5 have invented a certain new and useful Improvement in Feeding Rollers, of which the following is a full, clear, and exact description, such as will enable others skilled in the art to which it appertains to make and 10 use the same, reference being had to the accompanying drawings, forming part of this specification.

My invention relates generally to machines used in the manufacture of lumber, 15 and more particularly to a feeding roller that is specifically designed for use in various forms of lumber manufacturing machines, such as gang saws, edgers, and the like.

United States Letters Patent No. 1,242,020, dated October 2, 1917, No. 1,177,931, dated April 4, 1916, No. 1,208,294, dated December 12, 1916, and No. 1,241,925, dated October 2, 1917, disclose various forms of lumber 20 feeding rollers of the type to which my invention relates, and it is the principal object of my present invention to generally improve upon and simplify the construction 25 of the feeding rollers disclosed in the aforementioned patents as well as other types of feeding rollers now in general use, and, further, to provide a feeding roller which is particularly designed for exceptionally heavy work.

Obviously, the lumber fed to the relatively 30 large and heavy gang saws and edgers, is heavy and hard to handle. Consequently, it is necessary to make the feed rollers exceptionally strong and heavy so as to withstand the hard usage and stresses to which 35 they are subjected while in service. Therefore, it is one of the purposes of my invention to provide a feeding roller which is exceptionally strong for its size and weight and to provide a relatively simple and efficient construction which may be easily and 40 cheaply manufactured.

Further objects of my invention are, to provide a feeding roller in which the various parts are constructed and assembled 45 so that any part which becomes worn, broken, or unfit for service may be easily and quickly removed and replaced by a new part without necessitating the removal of the roller from its bearing or cessation of

the work of the machine for any appreciable 55 time.

Further objects of my invention are, to provide a feeding roller having lumber engaging teeth or projections which are interchangeable, thereby facilitating assembly 60 and replacement of parts, and likewise minimizing the cost of replacements, and further, to provide a feeding roller wherein the teeth or lumber engaging projections are continuous throughout the working length 65 of the roller, thus providing for the uniform engagement of the lumber during feeding operations, the insuring of the proper progressive forward movement, and likewise the holding of the lumber against lateral 70 movement during the forward feeding operations.

With the foregoing and other objects in view, my invention consists in certain novel features of construction and arrangement 75 of parts, hereinafter more fully described and claimed, and illustrated in the accompanying drawings, in which—

Figure 1 is an elevational view of a lumber feeding roller of my improved construction with a portion thereof in vertical section.

Figure 2 is an end elevational view of the feeding roller with the end shaft thereon in section.

Figure 3 is a cross section taken through the body of the roll with the lumber engaging teeth or members removed.

Figure 4 is a detail section of a portion of the roll and showing one of the tooth bars positioned in a slot in the body of the roll.

Figure 5 is an enlarged detail section of a portion of the roll and showing one of the tooth blocks positioned therein.

Figure 6 is a perspective view of one of the tooth bars utilized in my improved feeding roller.

Figure 7 is a perspective view of one of the tooth blocks.

Figure 8 is a detail sectional view showing modified forms of tooth bar and tooth block.

Referring by numerals to the accompanying drawings, which illustrate a practical embodiment of my invention, 10 designates the main body of the roll which is cylindrical in form, of any desired length, and pro-

vided at its ends with journals 11 whereby the feeding roller is mounted for rotation in suitable bearings.

The peripheral portions of the journals 11 immediately adjacent to the body 10 of the roll are externally threaded in order to receive suitable jam nuts 12 that are utilized for applying end pressure to the tooth bars and tooth blocks carried by the roll body 10, and the inner faces of these jam nuts are preferably countersunk or beveled as designated by 13 in order to engage the beveled or inclined ends of the adjacent tooth bars.

The peripheral portion of the cylindrical body 10 is provided with radially arranged longitudinally extending slots 14 of suitable width and depth and the inner portions of these slots gradually increase in width toward their bottoms, such construction being accomplished by the use of a suitable tool or cutter which engages and cuts away the lower portion of one of the side faces of each slot, and thus forming a beveled face 15. (See Fig. 4.) The longitudinally disposed lumber engaging teeth or ribs which project from the periphery of the feeding roller are made up of hardened metal tooth bars of the general form illustrated in Figure 6, and hardened metal tooth blocks of the general form illustrated in Fig. 7.

The tooth bars designated by the numeral 16 are formed of straight pieces or bars of relatively hard wear-resisting metal, each bar being several inches in length and having one of its edges rounded or beveled as designated by 17, the opposite edge 18, is left sharp and is adapted to engage the surface of the lumber during the feeding operations. The thickness of this tooth bar which is uniform throughout its length, is such that said bar will fit snugly within any one of the slots 14 in the body 10 of the roll and the width of said tooth bar is such that the outer portion thereof or that portion provided with the lumber engaging edge 18 projects a slight distance beyond the periphery of the body 10. (See Fig. 4.)

The ends of each tooth bar 16 are inclined or beveled inwardly and radially in opposite directions as designated by the numeral 19.

It will be understood that each groove 14, which extends the entire length of the body 10 of the roller, receives a plurality of the tooth bars 16 and when properly assembled, the outer inclined ends 19 of the outer pair of bars are engaged by the countersunk or beveled faces 13 of the jam nuts 12.

In order to rigidly secure the tooth bars 16 to the body of the roll and lock them in position in the grooves 14, relatively short blocks 20 of hardened metal are positioned in the grooves 14 between the adjacent ends of the tooth bars 16. Each of these blocks 65 has one of its outer edges rounder or beveled

off as designated by 21, the opposite edge 22 is left sharp and when the parts are properly assembled, alines with the corresponding edges 18 of the adjacent bars, thereby forming a practically continuous lumber engaging edge that extends throughout the length of the roller.

The blocks 20 are relatively short and their depth or measurement from top to bottom is slightly less than the depth of the tooth bars 16. The ends of said blocks 20 are inclined or beveled outwardly and radially as designated by 23 and when the tooth forming members are properly assembled, these beveled or inclined faces bear directly against the beveled or inclined ends 19 of the bars 16. The lower portion of each block gradually increases in width toward its bottom and this gradually widened lower portion fits snugly within the gradually widened lower portion of the groove 14 and when said block is properly positioned in the groove between a pair of the tooth bars, its bottom surface is slightly elevated with respect to the bottom surface of the groove 14. (See Fig. 5.)

When all of the tooth bars and blocks have been properly assembled in the groove 14, the jam nuts are manipulated upon the threaded portions of the journals so as to move toward the body of the roll, and as a result, pressure is applied to both ends of the rows of teeth formed by bars 16 and blocks 20, and such action very firmly and rigidly secures the tooth forming members to the body of the roll. As this end pressure is effected, the outer ends of the outer pair of bars 16 will be engaged beneath the countersunk inner faces of the jam nuts 12 and the inner ends of said outer pairs of bars and the ends of the intermediate bars will be positioned beneath the bevel ends of the blocks 20.

The end pressure applied to the tooth forming members will tend to force the blocks 20 outwardly, but such movement will be restricted by virtue of the fact that the lower portions of said blocks are considerably wider than the outer portions of the grooves 14. Consequently said blocks are retained in said grooves and in turn they are effective in securely anchoring the tooth bars 16 in said grooves.

Inasmuch as the tooth bars 16 are identical in size and construction and are interchangeable, and these same conditions apply to the tooth blocks 20, the manufacture of said parts is greatly simplified and the cost of renewal of parts is minimized.

The tooth bars 16 can be constructed in any desired manner, but preferably by being machined, and it is preferable that the tooth blocks 20 be drop-forged for this method of manufacture enables said blocks to be very accurately formed and at the

same time minimizing the cost of production.

While it is desirable to form continuous lumber engaging edges 18 on the bars 16 and continuous edges 22 on the blocks 20, it may be in some instances advantageous to notch the outer edges of the bars 16 at points intermediate their ends, as illustrated in Figure 8, and also to cut away the outer 10 corners of the tooth blocks 20, such construction producing interrupted edges at the outer ends of the lumber engaging members.

In the event that it is desired to remove one of the tooth bars or tooth blocks when the same has become worn or unfit for service, one of the jam nuts 12 is unscrewed so as to withdraw it a short distance from the ends of the adjacent tooth bars, after which, one or both of the tooth blocks in the row 20 from which the worn or broken member is to be removed is driven inwardly by blows delivered to its outer edge, which action loosens the block and permits it to be moved lengthwise a sufficient distance in the slot or 25 groove 14 to permit the bars 16 to be lifted bodily therefrom.

A feeding roller of my improved construction can be easily and cheaply produced, is exceptionally strong and durable, and is, therefore, particularly applicable for handling relatively heavy work, is constructed so as to present continuous lumber engaging edges on the ribs or teeth which extend throughout the length of the roller, and as a 30 result, the engaged lumber is firmly held against lateral movement during its forward feeding movement.

It will be readily understood that minor changes in the size, form and construction of the various parts of my improved feeding roller can be made and substituted for those herein shown and described, without departing from the spirit of my invention, the scope of which is set forth in the appended 45 claims.

I claim:

1. In a lumber feeding roll, a cylindrical body provided in its periphery with longitudinally disposed slots a plurality of tooth bars positioned in each slot, and tooth blocks arranged in said slots between said tooth bars, said tooth blocks having interlocking engagement with said slots and with said tooth bars.
2. In a lumber feeding roll, a cylindrical body provided in its periphery with longitudinally disposed slots, a plurality of tooth bars positioned in each slot, tooth blocks arranged in said slots between said tooth bars, said tooth blocks having interlocking engagement with said slots and with said tooth bars, and means on the cylindrical body for engaging the outer ends of the outer pair of tooth bars.
3. In a lumber feeding roll, a cylindrical body provided in its periphery with longitudinally disposed slots, a plurality of tooth bars positioned in each slot, tooth blocks arranged in said slots between said tooth bars, said tooth blocks having interlocking engagement with said slots and with said tooth bars, and means on said cylindrical body for engaging the outer ends of the outer pair of tooth bars.

body provided in its periphery with longitudinally disposed slots, a plurality of tooth bars positioned in each slot, tooth blocks arranged in said slots between said tooth bars, said tooth blocks having interlocking engagement with said slots and with said tooth bars, and means on said cylindrical body for engaging the outer ends of the outer tooth bars and applying end pressure to same and said tooth blocks to rigidly secure said tooth bars and the interposed tooth blocks to said cylindrical body.

4. In a lumber feeding roll, a cylindrical body provided in its periphery with longitudinally disposed slots, a plurality of tooth bars positioned in each slot, tooth blocks arranged in said slots between said tooth bars, said tooth blocks having interlocking engagement with said slots and with said tooth bars, and clamping means at the ends of said slots, said tooth bars and blocks in each groove being independently movable radially of said body but adapted to present a continuous lumber engaging edge when locked by said clamping means.

5. A lumber feeding roller comprising a cylindrical member provided in its periphery with longitudinally disposed slots, the inner portions of which are wider than their outer portions, a plurality of radially removable tooth bars positioned in each slot, and tooth blocks interposed between said tooth bars and engaging the ends of the latter against outward radial movement, the inner portions of which tooth blocks are widened so as to engage in the widened inner portions of the slots.

6. A lumber feeding roller comprising a cylindrical member provided in its periphery with longitudinally disposed slots, the inner portions of which are wider than their outer portions, a plurality of radially removable tooth bars positioned in each slot, tooth blocks interposed between said tooth bars and engaging the ends of the latter against outward radial movement, the inner portions of which tooth blocks are widened so as to engage the widened inner portions of the slots, and means for engaging the outer ends of the outer tooth bars to prevent longitudinal separation of same and the intermediate bars and tooth blocks and thereby lock the tooth elements to the cylindrical body.

7. A lumber feeding roller comprising a cylindrical body provided in its periphery with longitudinally disposed recessed slots, a plurality of tooth bars seated in each slot, tooth blocks positioned in the slots between said tooth bars, underlying said recessed slots and overlying the ends of the adjacent tooth bars.

8. A lumber feeding roller comprising a cylindrical body provided in its periphery with longitudinally disposed recessed slots,

a plurality of tooth bars seated in each slot, tooth blocks positioned in the slots between said tooth bars, underlying said recessed slots and overlying the ends of the adjacent 5 tooth bars, and means for holding the assembled tooth bars and tooth blocks against lengthwise movement upon the cylindrical member.

9. In a feeding roller, longitudinal radially-constricted grooves, tooth bars radially and longitudinally movable in said grooves and having ends inclined inwardly and radially, and tooth blocks longitudinally movable in said grooves, alternating with 10 said bars, having ends inclined outwardly and radially and being enlarged radially to fit said grooves.

10. In a feeding roller, longitudinal radially-constricted grooves, tooth bars radially and longitudinally movable in said grooves and having ends inclined inwardly and radially, tooth blocks longitudinally movable in 20 said grooves, alternating with said bars, having ends inclined outwardly and radially and being enlarged radially to fit said grooves, and means for preventing longitudinal movement of said tooth elements.

11. In a lumber feeding roller, a cylindrical member, a plurality of longitudinally disposed lumber engaging ribs carried by 30 said cylindrical member, each of which ribs comprises a plurality of tooth bars, and tooth blocks interposed between said tooth bars, which tooth blocks have interlocking engagement with the cylindrical member and with the adjacent tooth bars, said tooth members being slidable in said slots to disengage from each other, and means for preventing such slidable movement.

40 12. In a lumber feeding roller, a cylindrical member, a plurality of longitudinally disposed lumber engaging ribs carried by said cylindrical member, each of which ribs comprises a plurality of separately formed tooth bars radially removable from the cylindrical member, and a plurality of separately formed tooth blocks positioned between said tooth bars and having radially interlocking engagement with the cylindrical member and with the adjacent tooth bars.

13. In a lumber feeding roller, a cylindrical member, a plurality of longitudinally disposed lumber engaging ribs carried by 55 said cylindrical member, each of which ribs comprises a plurality of separately formed tooth bars radially removable from the cylindrical member, a plurality of separately formed tooth blocks positioned between said tooth bars and having radially interlocking

engagement with the cylindrical member and with the adjacent tooth bars and longitudinally removable from said member, and means for holding the assembled tooth bars and tooth blocks against longitudinal movement upon said cylindrical member. 65

14. In a lumber feeding roller, a cylindrical member provided in its periphery with longitudinally disposed grooves, and lumber engaging members removably seated in said grooves and projecting beyond the periphery of the cylindrical member, which lumber engaging members extend substantially the entire length of the cylindrical member, each of which lumber engaging members comprises a plurality of tooth bars radially removable and tooth blocks locked against radial removal but longitudinally removable and adapted to engage said tooth bars to prevent radial removal thereof, and means for 70 preventing longitudinal movement of said tooth elements. 75

15. In a lumber feeding roller, a cylindrical member provided in its periphery with longitudinally disposed grooves, and lumber engaging members removably seated in said grooves and projecting beyond the periphery of the cylindrical member, which lumber engaging members extend substantially the entire length of the cylindrical member, each of which lumber engaging members comprises a plurality of alternate tooth bars and tooth blocks, which latter have interlocking engagement with the cylindrical member and with said tooth bars. 85 90 95

16. In a feeding roller, longitudinal radially-constricted grooves, tooth bars radially and longitudinally movable in said grooves and having ends inclined inwardly and radially, tooth blocks longitudinally movable in said grooves, alternating with said bars, having ends inclined outwardly and radially and being enlarged radially to fit said grooves, and means clamping said tooth elements longitudinally, thereby forcing said tooth blocks outwardly against radially converging sides of said grooves and forcing said tooth bars inwardly against the bottoms of said grooves. 100 105

17. In a feeding roll, longitudinal grooves, radially removable tooth elements seated in said grooves and forming a continuous tooth surface, means for clamping said elements lengthwise in said grooves, said elements when so clamped being adapted to be positively locked intermediate their ends against radial removal from said roll. 110 115

In testimony whereof I hereunto affix my signature this 15th day of April, 1921.

THOMAS C. MORRIS.
